Primary Examiner—Susan J. Lucas*Assistant Examiner*—Cynthia Ramirez**[57]****CLAIM**

The ornamental design for an ice scraper, as shown and described.

DESCRIPTION

FIG. 1 is a perspective view of an ice scraper showing my new design;

FIG. 2 is a top plan view thereof, the bottom being a mirror image;

FIG. 3 is a top plan view of a second embodiment of my design, the bottom being a mirror image;

FIG. 4 is a side elevational view of a third embodiment of my design, the third embodiment differing from the second embodiment only by the inclined scraping end; and,

FIG. 5 is a top plan view of a fourth embodiment, the bottom being a mirror image.
